TUBULAR ELECTRIC HEATING ELEMENT
AND METHOD OF MAKING THE SAME

Christian B. Backer, Ottawa, Ontario, Canada

Application April 18, 1946, Serial No. 663,201
In Canada May 12, 1945

6 Claims. (Cl. 201—67)

1

This invention relates to tubular electric heating elements and method of producing the same.

The invention has particular relation to a common type of electric heating element which is now in widespread use and which comprises an outer metallic tube or sheath, a centrally located resistance wire coil within the sheath, and electric insulation between the coil and sheath, the electric insulation consisting of crystalline magnesium oxide produced in situ.

The procedure heretofore followed in the production of these elements is to insert into the outer tube or sheath a magnesium metal lining, which may consist of a wound up magnesium ribbon, or of several longitudinal magnesium strips bent into segmental form, or of a seamless magnesium tube. The resistance wire coil is inserted in the center of this assembly and held in place by a suitable clip at each end of the tube. The magnesium is then converted into magnesium hydroxide by treatment in an autoclave with steam or water at high pressure and temperature. It will be realized that the component parts of the assembly must be so arranged that the water or steam may flow through the tube and come into contact with the magnesium metal to be converted. The hydrated magnesium (magnesium hydroxide) occupies substantially twice the space originally filled by the magnesium liner. Thus as hydration proceeds the liner grows in volume contacting the resistance coil and portions of it are forced between the convolutions of the coil. Usually substantially one half of the circumferential surface of the wire is surrounded by the magnesium hydroxide and the surface of the portions of the latter exposed between the convolutions of the coil progressively become so hard and dense that hydration is greatly retarded. Accordingly, while much of the magnesium of the liner is hydrated in a short time after the pressure in the autoclave reaches 300 to 400 pounds per square inch, hydration of the remaining portion requires a pressure of about 1000 pounds per square inch for a period of several hours. This is due to the fact that the pressure of the coil makes it obligatory for portions of the expanding liner to be densely compacted within the narrow spaces between the convolutions of the coil leaving a greatly restricted surface area of dense material through

2

which the hydrating agent must penetrate to complete the hydration of the magnesium of the liner. The hydrating operation thus consumes 8 to 10 hours and sometimes longer and requires high pressure for much of that time to insure effective hydration. This is an expensive and time-consuming operation.

Furthermore insertion of the resistance coil prior to hydration makes it difficult to provide 10 a cool terminal for the element. In order to permit passage of the hydrating medium into and throughout the element to hydrate the magnesium of the liner the end of the resistance wire is brought outside the element for subsequent 15 attachment of the terminal member. If the terminal member were attached to the resistance wire at a point within the small tubular element it would interfere with admission of the hydrating medium. The resistance wire extending to 20 the end of the element causes generation of undesirable heat in the end portions of the element, giving rise to hot terminals. The only step that can be taken towards attaining cool terminals is to run the resistance wire straight (instead 25 of coiled up) for a suitable distance near both ends of the element tube, but even a straight resistance wire generates considerable heat. To fix the resistance coil to a solid and fairly heavy terminal member, which may extend several 30 inches into the tube, is impossible, because it would block up the passage of water through the tube during conversion. The problem of attaining cool (or reasonably cool) terminals has therefore caused great manufacturing difficulties in 35 the production of this type of tubular element.

It is an object of the present invention to provide a method of producing a tubular electric heating element of the type described wherein the step of converting the magnesium metal into hydroxide is effectively and completely accomplished in a rapid and inexpensive manner and whereby the association of a satisfactory terminal construction is rendered convenient and free from manufacturing difficulties.

The invention contemplates the provision of a magnesium hydroxide lining in a sheath prior to, instead of after, the insertion of the resistance coil into the sheath, it having been found that when the coil, which interferes greatly with the conversion process, is not present, the con-

version treatment proceeds much more rapidly and at a reduced pressure. It has also been found that there may be produced a completely satisfactory element wherein the resistance coil fits snugly within the hydroxide lining but is not embedded therein during hydration.

The invention will be described with reference to the accompanying drawing, in which

Figure 1 is an enlarged sectional elevation of an end portion of a tubular element in accordance with the invention, and

Figure 2 is a transverse sectional view.

In accordance with the invention, a preferably seamless magnesium metal tube is inserted into a metal sheath 1. The assembled sheath and tube are then placed in an autoclave and the magnesium tube converted to the hydroxide with steam or water. Since the central opening in the magnesium tube is wide open and completely unobstructed, the water or steam passing through this opening is free to contact the whole surface of the liner and the expanding liner is not subjected to compacting pressure. Conversion of the metal therefore proceeds rapidly and may be completed in from two to four hours at 200 to 500 pounds pressure at the corresponding temperature for saturated steam, instead of from eight to ten hours at 1000 pounds pressure when the tube opening is obstructed by the resistance coil, as in the usual method. As the tube comes from the autoclave a lining 2 is substantially completely hydrated, is of uniform density throughout its length and has a smooth circular bore into which the resistance coil 3 may now be inserted. The resistance coil may have a terminal bar or rod 4 of relatively low electrical resistance and greater cross section than the wire at each end, and this terminal member may extend into the sheath for any desired distance. A simple manner of attaching the resistance coil to the inner end of the terminal member is to provide such member with a screwthread 5 for a distance of, say, about $\frac{1}{16}$ ". The end 6 of the resistance coil is then screwed onto the threaded terminal member, a tight fit being required. While it is old to so fix a resistance coil to a terminal, this type of engagement could not heretofore be employed in a tube element with insulation formed in situ from magnesium metal, when the usual method of assembling all the parts before treatment in the autoclave was followed.

It will be understood, however, that any suitable method of fixing the resistance coil to the terminal member may be followed. Thus, where the resistance wire is extremely heavy and it would be impractical to screw it onto the terminal, a small hole (slightly larger than the diameter of the resistance wire) may be drilled longitudinally in the end of the terminal member to a depth of about $\frac{3}{16}$ ", the straightened end of the resistance coil inserted in the hole, and the end of the terminal member pressed square to clinch the wire in the hole.

The outside diameter of the resistance coil should be made about two or three thousandths of an inch smaller than the bore of the magnesium hydroxide lining. The resistance coil, with its terminal members attached, is passed into the central bore and a suitable clip at each end of the sheath employed to hold the coil and terminal members in place while a refractory insulation powder, indicated at 7, is poured into the tube to fill the central opening in the resistance coil as well as the slight clearance space

between the terminal members and the magnesium hydroxide lining. When the tube has been filled with the insulation powder to within about $\frac{1}{2}$ " from its ends, the terminal members will remain in place while a suitable non-hygrosopic insulation powder 8 is packed around the ends of the terminal members to hold them firmly in place.

The element is finally dried at high temperature to convert the magnesium hydroxide into magnesium oxide, and subjected to compression to compact the assembly. Such compacting of the assembly prevents cracks in the magnesium oxide insulation and insures uniform distribution of the insulation about the coil and terminal member. Because of the uniform density of the material of the liner produced by the present method the crystal particles are free to move uniformly under the compacting stress and even sharp turns of the element may be made without disturbing the continuity of the insulation.

While the terminal members may be formed from any suitable material, a nickel-chromium-iron alloy, which will not oxidize at the high temperatures at which the element is dried, is to be preferred.

It will be understood that the outside tube or sheath, containing the magnesium tube, may be treated in any length up to the full length of the available autoclave, and the tube thereafter cut up into any lengths required for the heating elements in question.

Manufacturing of the elements is thus greatly simplified and labour costs in producing tubular elements by the method of the present invention are generally not greater than half those of the usual method as previously outlined.

I claim:

1. A method of making tubular electric heating elements which comprises inserting a magnesium metal liner into an outer tubular sheath, hydrating the metal of the liner while maintaining the bore of the liner free from obstruction to produce an expanded lining of magnesium hydroxide having a cylindrical bore therein of substantially uniform cross-section, and thereafter inserting a resistance coil into the bore of the resultant magnesium hydroxide lining.

2. A method of making tubular electric heating elements which comprises inserting a lining of magnesium metal into an outer tubular sheath, hydrating the metal of the lining to form an expanded magnesium hydroxide lining of uniform density and having a cylindrical bore therein of substantially uniform cross-section, and thereafter inserting a resistance coil having terminal members attached thereto into the bore of the resultant magnesium hydroxide lining with each said terminal member having a portion thereof extending within said cylindrical bore.

3. A method of making tubular electric heating elements which comprises inserting a substantially seamless lining of magnesium metal into an outer tubular sheath, hydrating the metal of the lining to form an expanded magnesium hydroxide lining of uniform density and having a cylindrical bore therein of substantially uniform cross-section, inserting a resistance coil having terminal members attached thereto into the bore of the resultant magnesium hydroxide lining with each said terminal member having a portion thereof extending within said cylindrical bore, filling the central opening of the resistance coil and the clearance between the terminal members and the lining with refractory powder, dry-

ing the assembly to convert the magnesium hydroxide to magnesium oxide, and swaging the sheath to compact and uniformly distribute the insulation around the resistance coil.

4. A method of making tubular electric heating elements which comprises inserting a tubular magnesium substantially seamless liner into a tubular sheath, subjecting the assembly to steam at a pressure of substantially 200 to 500 pounds per square inch and at the corresponding temperature for saturated steam for a period not substantially exceeding four hours to hydrate the magnesium and form an expanded liner of uniform density and having a cylindrical bore there-
in of substantially uniform cross-section through-
out its length and thereafter inserting an electric
resistance element into said cylindrical bore. 15

5. A method as defined in claim 4 wherein a terminal rod is attached to the resistance element before the latter is inserted in the liner, 20 said terminal rod having a portion thereof ex-
tending within said cylindrical bore.

6. A method of making tubular electric heating elements which comprises inserting a substan-
tially seamless lining of magnesium metal into 25 an outer tubular sheath, hydrating the metal of
the lining while maintaining the bore of the
lining free from obstruction, thereafter inserting
a resistance coil having terminal members at-

tached thereto into the bore of the resultant magnesium hydroxide lining with each said terminal member having a portion extending within said bore, filling the central opening of the resistance coil and the clearance between the terminal members and the lining with refractory powder, packing a non-hygrosopic insulation powder around the terminal members at both ends of the sheath to hold them in place, drying the assembly to convert the magnesium hydroxide into magnesium oxide, and swaging the sheath to uniformly compact the insulation around the resistance coil.
